OF SWEDEN

ELECTROMAGNETIC RELAY

Application filed June 12, 1929, Serial No. 370,181, and in Sweden October 15, 1923.

The perpetually increasing demand for safety in the operation of electric distribution systems lead to corresponding, more and more increasing demands on the relays serving to protect the systems, as regards the sensitivity and reliability of the said relays. The sensitivity implies that the relay shall be able to develop strong forces with a small consumption of power. The reliability depends on many factors, among which one of the most important is that the curve expressing the relation between the displacement of the movable part and the force developed shall have an appropriate course. Another circumstance influencing the reliability is the behaviour of the relay on the occasion of heavy overloads. Particularly in very sensitive relays which are normally intended to be actuated by weak currents, a rise of current above a certain value is generally accompanied by accessory phenomena which may hazard the regular function of the relay.

The present invention relates to a relay which is principally intended to operate as a current relay and which is distinguished by a great sensitivity as well as a great reliability. The sensitivity depends mainly on the fact that the armature forms the smallest possible portion of the magnetic circuit. For this purpose, the stationary portion of the magnetic core is interrupted only for a short interval for leaving space for the armature which is movable substantially at right angles to the flux path of the core. The length of the interval should be smaller than, equal to or slightly greater than the length of displacement of the armature. The latter has preferably a U-shaped cross-section, whereby two advantages are gained. First, the weight of the armature will, for the same air-gap dimensions, be considerably smaller than of a solid one, whereby the sensitivity is increased. Secondly, the flux is compelled to traverse a certain length through iron of a comparatively small cross-section, whereby for large currents a high saturation is reached, thus reducing the air gap flux and consequently the attractive force so that the latter cannot exceed a certain value. This is desirable owing to the fact that a too large

attractive force causes risk for heavy vibrations as soon as the relay is operated by alternating current, such vibrations being likely to cause repeated interruptions of current and thereby a burning of the contacts.

A form of the invention is illustrated in the accompanying drawing. Figure 1 shows the magnetically active portions of the relay in an end view, Figure 2 the entire relay in a side view, and Figure 3 a detail of Figure 2 on a larger scale. Figure 4 shows some curves characteristic to the relay.

Referring to Fig. 1, 1 is the main portion of the stationary magnet core of the relay, which core may be laminated in the usual manner and is composed of two legs carrying coils and a lower yoke. In the form shown, the core is also provided with an upper yoke 2 which is interrupted only for a short distance so as to leave space for the movable armature 3. The latter consists preferably of a single sheet iron piece bent in U-shape, the side pieces of which limit the two air gaps of the relay, while the intermediary bridge piece conducts the flux between the side pieces. As the relay is normally intended to operate for very weak currents and thus with weak fluxes in the air gaps, the thin bridge piece of the armature is normally sufficient to conduct the entire flux without being saturated. At high overcurrents, which always are likely to occur, the restricted flux path through the bridge causes a limitation of the flux in the air gap, the consequence hereof being that the armature is not subjected to forces of too great magnitude which would give rise to disturbances. In order to further enforce this limitation of the flux, the yoke 2 may also, as shown in the drawing, consist of simple sheet-iron pieces of which the ends facing the armature are bent to be substantially parallel to the side pieces of the armature.

In relays in general and particularly in such where a high sensitivity is desired, it is important that the curve expressing the relation between the movement of the armature and the attractive force acting thereon has an appropriate shape. The movement of the armature is generally counteracted by

a spring which in Figure 2 of the drawing is designated by 4. In the same figure, the armature 3 is shown as mounted on a long lever 5 capable of being swung around a pivot 6 in a stand 7 and actuated by the said spring 4. The counter-force exerted by the latter generally increases in proportion to the displacement and may in Fig. 4, where the abscissæ represent the said displacement and the ordinates the forces, be represented by the straight line *a*. Towards the end of the displacement of the armature, an elastic contact device shall be actuated with a sufficient force for accomplishing a certain pressure between the contacts. The latter are in Fig. 2 designated by 8 and 9 and in Fig. 3 shown together with the adjacent portion of the lever 5 on a larger scale, in the original position in full and in the final position in dotted lines. It is easily seen that an additional counter-force arises at the end of the movement by reason of the elasticity of the contact 9, so that the total counter-force during this portion of the movement can be represented by the straight line *b* in Figure 4. In order that the relay shall operate in a satisfactory manner it is desirable that the curve *c* expressing the relation between magnetic force and displacement should follow the broken line *a*, *b* as closely as possible and intersect it at no place after the movement has begun, as this would cause uncertainty in the function and particularly a bad contact pressure. The curve *c* should therefore primarily rise at a comparatively constant rate in its major portion. This can be accomplished by making the upwardly directed portions of the yoke 2 and armature 3 oblique so as to cause the air gap to decrease as the armature is pulled into the interval in the yoke. Further, however, the curve *c* should be considerably steeper towards the end corresponding to the final attraction. In order to achieve this, a pair of auxiliary pole pieces 10 are preferably arranged inside the yoke 2 so as to cause an increased attraction on the armature towards the end of its movement. These auxiliary pole pieces also preferably consist of simple sheet iron whereby the advantage is gained among others that the last portion of the curve *c* can be adjusted to an appropriate shape by a slight deformation of the said pieces.

I claim as my invention:—

- 55 1. In electromagnetic relays, a stationary magnet core having bent sheet iron pieces limiting an interval and a U-shaped armature movable into said interval.
- 60 2. In electromagnetic relays, a stationary magnet core having diverging surfaces limiting an interval and a U-shaped armature having correspondingly divergent side pieces movable into said interval.
- 65 3. In electromagnetic relays, a stationary magnet core having an interval, an armature

moving sidewise with respect to the flux in said core into said interval, and auxiliary pole pieces limiting an interval adjacent to said first interval and on the side of the core towards which the armature is moved when attracted.

4. In electromagnetic relays, a stationary magnet core having an interval, an armature moving sidewise with respect to the flux in said core into said interval, and auxiliary pole pieces limiting an interval and consisting of sheet iron adjacent to said first interval and on the side of the core towards which the armature is moved when attracted.

In testimony whereof I have signed my name to this specification.

WILHELM HENNING PETERSÉN.
